UNITED STATES PATENT OFFICE

LEO L. BECK, OF JACKSON HEIGHTS, NEW YORK, ASSIGNOR TO CLAUDE NEON LIGHTS, INC., OF NEW YORK, N. Y., A CORPORATION OF NEW YORK

METHOD OF AND APPARATUS FOR MODIFYING COLOR OF VACUUM TUBE LIGHTS

Application filed September 8, 1927. Serial No. 218,182.

This invention relates to lighting systems, such, for example, as that comprising the well known neon lights, in which the passage of a high potential alternating current through a column of more or less rarefied gas, such as neon, causes the tube contents to glow and radiate light. 5

Heretofore, the color of light emitted by the contents of a luminescent tube has not 10 been modified permanently or even for a predetermined prolonged period. A momentary modification of the light emitted from a gaseous mixture enclosed in a luminescent tube has been produced by abruptly varying 15 the current passing through the tube, but this has obviously not resulted in a permanent maintenance of the modified color. With a mixture of gases and metallic vapors, such as neon and mercury vapor, one alone of the 20 components has been caused to vibrate under the action of the electric discharge between the terminals and has emitted its characteristic color, that is, the same color as if it were alone contained within a tube. Either 25 the neon gas alone commenced to vibrate or the mercury vapor alone commenced to vibrate depending upon conditions, but it has heretofore been found impossible, in a given portion of the tube, to obtain a mixture of 30 light from both the neon gas and the mercury vapor which was of a color applicable to lighting.

The present invention seeks a stable manner of obtaining a modification of the color 35 of the light emitted by a luminescent tube. To this end the color of the light emitted by such a tube is varied or modified and the modified color maintained constant or stable by changing the frequency of the alternating 40 current passing through the tube.

The color obtained from a pure gas enclosed in a luminescent tube, electrically excited, depends upon the number of the rays in the spectrum, on the position of the rays in 45 the spectrum and on the comparative intensity of the rays. The number of the rays and their position in the spectrum do not change, whatever may be the process utilized to produce the spectrum and this constitutes a constant characteristic of the gas. The com- 50

parative intensity of the rays may be affected, however. The color of the light depends upon the comparative intensity of the rays and it is by affecting this condition that the modification of the light in accordance with 55 this invention is obtained.

For example a tube filled with pure neon emits a red orange light at a low frequency, say 60 cycles, whereas at a higher frequency it will emit a yellow orange light. At low 60 frequency the green rays are the more intense. This is a common characteristic of such gases. For instance, helium, excited at low frequency, emits a pinkish yellow light whereas at high frequency the light is more 65 of a violet color. This is because at a low frequency the red and yellow rays predominate whereas, at a higher frequency, the violet rays predominate. With a mixture of a gas, 70 say neon, and a vapor, say mercury vapor, in a luminescent tube, the mercury vapor vibrates alone at low frequency and the tube emits a blue light. If the excitation is effected at high frequency the neon vibrates 75 at the same time as the mercury and there may be observed in the spectrum the simultaneous presence of the spectrum of neon and the spectrum of mercury and this is stable. The light thus emitted by the tube is neither 80 the blue of the mercury nor the reddish color of the neon gas but is a mixture of the two and is of a pinkish color. With a mixture of helium and mercury vapor, at low frequency, the tube emits a greenish light while at high frequency the tube emits a yellowish light. 85

The object of the present invention is an apparatus by which the foregoing results may be realized. In carrying out the invention a vacuum tube is included in an oscillating circuit. The voltage is, of course, maintained at a high value, as that is a well known requirement for the operation of rarefied gas tubes. The necessary high voltage is conveniently obtained from the usual industrial supply by means of a transformer. To effect 90 the variation in the color of the light usually emitted from the vacuum tube and to maintain that color constant under unchanging conditions the frequency of the current fed to the tube is increased materially over the 100

normal frequency by suitable frequency changing devices included in the circuit with the transformer. The invention also seeks to permit a selection, as desired, of the altered 5 color or the usual color emitted by the tube contents. To this end provision is made for selectively connecting the lamp with either a high frequency oscillating circuit or with a source of high potential low frequency oscillating current.

These and other objects of the invention and the means for their attainment will be more apparent from the following detailed description of a preferred embodiment there- 15 of, taken in connection with the accompanying drawing which illustrates, conventionally, a rarefied gas tube, adapted for selective connection with either low frequency circuit or a non-oscillating circuit.

20 In the lighting system as illustrated the tubular envelope 6 of the tube light containing a rarefied gas, such as neon, or helium or like alone, or mixtures of such gases or a mixture of a gas with a metallic vapor, such 25 as mercury vapor, is shown as having bulb portions 7 carrying electrodes 8 mounted on lead-in wires 9 and 10 respectively, each passing through a press 11. The tube 6 is connected by the leads 9 and 10 with either an 30 oscillating circuit of high frequency or an oscillating circuit of low frequency.

Referring first to the low frequency oscillating circuit a source of low potential alternating current is indicated at G connected 35 with main conductors 15 and 16 which may represent the usual industrial alternating current supply at, say a frequency of 60cycles. These mains 15 and 16 are connected, respectively to the terminals 11 and 12 of a circuit 40 selecting device, such as a double pole switch 13, by which an electrical connection may be selectively made with either the high frequency oscillating circuit or the low frequency oscillating circuit. Obviously this selection of 45 circuits may be made manually by means of the switch 13 as shown, or mechanically, to throw in the respective circuits periodically in predetermined manner.

To operate the tube 6 for the purpose of 50 obtaining the usual light emitted by the tube contents at normal frequency, the mains 15 and 16 are respectively connected by the circuit selector 13 with the contacts 2 and 4 which are connected by the leads 18 and 19 with the 55 terminals of the primary coil 20 of the transformer 21. The secondary coil 22 of the transformer 21 is connected with the leads 9 and 10 by the wires 23 and 24 so that the tube 6 may be electrically connected with 60 the transformer 21 and operated from the commercial supply mains 15 and 16 at the requisite high potential, but at normal frequency, in a manner well understood, to give the characteristic color of the vacuum tube light.

The transformer 21 may take any form suitable to the situation, that is, it may be a leak transformer in order that it may compensate for the negative resistance of the tube or if an ordinary commercial transformer is used, a reactance or other current controlling device (not shown) may be included in the circuit for the same purpose, as will be understood.

70 For the operation of the tube 6 at high frequency, in the attainment of a modification of a color emitted by the tube contents the tube is included in a high frequency oscillating circuit. The switch 13 is availed of to disconnect the source of current of normal frequency from the low frequency oscillating circuit and connect the said source with the high frequency oscillating circuit, including the switch contacts 1 and 3, such as will now be described.

80 Connected with the leads 9 and 10 of the tube 6 as by the wires 25 and 26 and in parallel with the secondary coil 22 just described is the primary coil 27 of the transformer 28 whereof the secondary coil 29 is included in 90 the oscillating circuit through the wires 31, 32 leading to the contacts 1 and 3 of switch 13.

95 The constants of the oscillating circuit are so designed as to permit the tube 6 to be operated through the instrumentality of the transformer 28, at a much higher frequency, say 5000 cycles, than when operated from the transformer 21 by including frequency changing means in the oscillating circuit with transformer 28.

100 Terminal 1 may be connected at one terminal of the primary coil 29 by the lead 31 while a condenser 33 is interposed in series with switch terminal 3 and the other terminal of the primary coil 29 and across the condenser there is shown connected a current breaker 34.

105 It will thus be seen that by the circuits described and by properly proportioning the constants of the circuit, the comparative intensity of the rays of the spectrum of the tube contents may be modified and thus the color of the light therein produced, modified.

110 Furthermore, by the disposition of the component elements disclosed, the operation of the tube, commercially, with apparatus as now developed may be realized and the substitution of any well known form of primary flasher for the switch 13 is permitted without incurring the liability to destructive arcing were a circuit delivery high frequency alternating current to be selectively interconnected with the leads 9 and 10 of the tube 6.

115 In addition the disconnection of the low frequency circuit obviates any power loss in the primary coil of transformer 20 as would be the case were that coil continuously fed by the mains 15 and 16, while the secondary coil 22 although in parallel with the tube 6 will 120 not shunt the tube due to the fact that its 125

impedance may be made sufficiently high as compared with the resistance of the tube.

In utilizing this process it is possible to obtain changes of color in the same tube, which can be prolonged at will and can be used for luminous advertising. For example, the tube may be alternately fed, first with the alternating current at low frequency in the usual way as indicated by the circuit 10 including the transformer 21 to cause the tube to radiate light of its characteristic color or it may be supplied as desired with a high frequency current, as by the circuit including the transformer 28 and the tube will instantly light up with an altered color which may be maintained as long as desired. Furthermore, the intervals of time between operating the tube at low frequency and high frequency may also be prolonged as desired, 20 which differentiates the process from those prior known experiments in which a temporary instantaneous change in color is obtained by varying the current.

Various substitutions may be made among 25 the component elements of the circuits by which the invention is shown as being realized. Furthermore the invention is not to be deemed limited to a combination including both an oscillatory circuit and a non-oscillatory circuit but the inclusion of the non-oscillatory circuit is to be deemed permissive and has been illustrated in order to show the widest usefulness of the invention.

What I claim is:

35 1. A lighting system comprising the combination with a luminescent tube and a source of alternating current at low frequency and low voltage, of a transformer whereof the secondary coil is connected with the tube terminals, a high frequency oscillatory circuit including the primary coil of the transformer and a circuit closing device selectively connecting the source of current at low frequency and voltage with the high frequency oscillatory circuit.

2. A lighting system comprising the combination with a luminescent tube and a source of alternating current at low voltage and frequency, of a transformer whereof the secondary coil is in circuit with the tube, a low frequency circuit including the primary coil of the transformer adapted to be connected to the source of alternating current, a second transformer whereof the secondary coil is in circuit with the tube in parallel with the secondary coil of the first named transformer, a high frequency oscillatory circuit including the primary coil of the second transformer and means to selectively connect the high frequency and low frequency circuits with the source of low voltage alternating current.

3. A lighting system comprising the combination with a luminescent tube and a source of alternating current at low frequency and low voltage, of a transformer whereof the

secondary coil is in circuit with the tube, a low frequency circuit including the primary coil of the transformer, a second transformer whereof the secondary coil is in circuit with the tube in parallel with the secondary coil of the first named transformer, a high frequency circuit including the primary coil of the second transformer, means to selectively connect the high frequency oscillatory and low frequency circuits with the low voltage source of alternating current, and means to prevent either secondary coil shunting the tube.

4. A lighting system comprising the combination with a luminescent tube and a source of alternating current at low frequency and low voltage, of a transformer whereof the secondary coil is in circuit with the tube, a circuit including the primary coil of the transformer, a second transformer whereof the secondary coil is in circuit with the tube in parallel with the secondary coil of the first named transformer, a high frequency oscillatory circuit including the primary coil of the second transformer and means to selectively connect one of the two circuits with the source of low voltage alternating current, the secondary coil of the second named transformer having an impedance relatively higher than the resistance of the tube.

5. A lighting system comprising the combination with a luminescent tube and a source of alternating current at low frequency and low voltage, of a transformer whereof the secondary coil is in circuit with the tube, a low frequency circuit including the primary coil of the transformer, a second transformer whereof the secondary coil is in circuit with the tube in parallel with the secondary coil of the first named transformer, a high frequency oscillatory circuit including the primary coil of the second transformer and means to selectively connect the high frequency oscillatory and low frequency oscillatory circuits with the source of low voltage alternating current, the secondary coil of the first named transformer having an impedance relatively higher than the resistance of the tube.

6. A lighting system comprising the combination with a luminescent tube and a source of alternating current at low frequency and low voltage, of a transformer whereof the secondary coil is in circuit with the tube, a low frequency oscillatory circuit including the primary coil of the transformer, a second transformer whereof the secondary coil is in circuit with the tube in parallel with the secondary coil of the first named transformer, a high frequency oscillatory circuit including the primary coil of the second transformer and means to selectively connect the high frequency oscillatory and low frequency oscillatory circuits with the source of low voltage alternating current, the impedance of the

secondary coils of both transformers being relatively greater than the resistance of the tube.

7. A lighting system comprising in combination a luminescent tube charged with a mixture of two gases or vapors or a gas and vapor, a source of alternating current at low frequency and low voltage, means connected to the tube to transform the low voltage to a high voltage, means connected to the tube to transform the low voltage and frequency to a high voltage and high frequency, and means to selectively connect the source of low voltage alternating current to one of the said means.
8. A lighting system comprising the combination with a luminescent tube containing mercury and a rare gas and a source of alternating current at low frequency and low voltage, of a transformer whereof the secondary coil is connected to the tube terminals, a high frequency circuit including the primary coil of the transformer, and a circuit closing means adapted to selectively connect the source of alternating low voltage current with the high frequency circuit.
9. A lighting system comprising a luminescent tube, a low frequency circuit and a high frequency circuit connected to said tube, a source of low voltage and low frequency current, and a circuit closer interposed between said low voltage source of current and said low and high frequency circuits and adapted to connect either of said circuits with said source of low voltage current.
10. A lighting system comprising a luminescent tube containing a rare gas and mercury, a low frequency circuit and a high frequency circuit connected to said tube, a source of low voltage and low frequency current, and a circuit closer interposed between said low voltage source of current and said low and high frequency circuits and adapted to connect either of said circuits with said source of low voltage current.

In testimony whereof I affix my signature.
LEO L. BECK.

CERTIFICATE OF CORRECTION.

Patent No. 1,827,704.

Granted October 13, 1931, to

LEO L. BECK.

It is hereby certified that error appears in the printed specification of the above numbered patent requiring correction as follows: Page 2, line 18, for the word "low" read a high, and line 19, for the compound word "non-oscillating" read low frequency; line 101, for "at" read to, and line 121, for "delivery" read delivering; and that the said Letters Patent should be read with these corrections therein that the same may conform to the record of the case in the Patent Office.

Signed and sealed this 8th day of December, A. D. 1931.
